Design No. 3194

B. D. Beiderhase's Design Spoon Handle.

Fig. 1.

Fig. 2.

IN THIS DESIGN

PATENTED
APR 10 1895

United States Patent Office.

B. D. BEIDERHASE, OF NEW YORK, N. Y.

Design No. 3,194, dated September 22, 1868.

DESIGN FOR A SPOON-HANDLE.

The Schedule referred to in these Letters Patent and making part of the same.

TO ALL WHOM IT MAY CONCERN:

Be it known that I, B. D. BEIDERHASE, of the city, county, and State of New York, have invented a new and improved Design for Spoon-Handle; and I do hereby declare that the following is a full, clear, and exact description thereof, which will enable others skilled in the art to make and use the same, reference being had to the accompanying drawings, forming part of this specification.

This invention relates to an improvement in spoons, and consists in a design for the ornamentation of the upper and under surfaces of the handle.

Figure 1 is a longitudinal view of the upper or face side of the spoon.

Figure 2 is a longitudinal view of the under or rear side.

Similar letters of reference indicate corresponding parts.

The upper surface of the handle is ornamented by a heavy raised border-line, *a*, which commences and terminates in a scroll at the base of the flat portion of the handle, as seen at *b*.

From the flat portion to the junction of the handle with the bowl of the spoon, the handle is slightly oval in form, (in cross-section,) and is also somewhat enlarged in its central portion, as seen at *c*, with the upper part of the oval handle surrounded by a bead, *d*.

e is a slightly-tapering raised central line, which extends from the oval portion, and terminates at the base of an oval shield, *f*.

The shield *f* is capped by a crown of leaves, *g*, and occupies the upper central part of the flat portion of the handle.

The lower portion of the shield terminates in light scrolls on each side of the point of the line *e*. The spaces between this central line *e* and the heavy border-line *a* are filled in with arabesque scroll-work, as seen in the drawing.

This arabesque work also surrounds the shield.

The flat portion of the handle is tapering in its lower portion, and made broad opposite the upper part of the shield, as seen at *h h*, from which points the edges recede at an angle of about forty-five degrees with the central line to the point *i*.

This angular edge is broken by an indentation on each side, as seen at *j j*, around which the border-line *a* extends.

The under side of the handle is ornamented with a heavy raised line, extending all around the edge, and terminating in scrolls at the base of the flat part, as on the upper side.

The central tapering line *e* is also produced on this side of the handle.

The space between the raised border-line *a* on the back side is left plain, without other ornamentation than the central line *e*.

At the junction of the handle with the bowl of the spoon there is a figure in arabesque, on each side, as seen in the drawing.

Having thus described my invention, what I claim as new, and desire to secure by Letters Patent, is—
A design for a spoon-handle, as shown and described.

B. D. BEIDERHASE.
